Primary Examiner — Terry A Wallace(57) **CLAIM**

The ornamental design for an insulated container, as shown and described.

DESCRIPTION

FIG. 1 is a front perspective view of an insulated container showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dot-dash broken line represents a boundary of the claimed design. The dash-dash broken lines throughout the drawing figures depict portions of an insulated container that form no part of the claimed design. The broken lines and unshaded surfaces bounded by broken lines form no part of the claimed design.
